(57) **CLAIM**

The ornamental design for a wireless digital kitchen thermometer system, as shown and described.

DESCRIPTION

The wireless digital thermometer system is comprised of a Remote Display and Control Unit as shown in FIGS. 1-7 and a Remote Sensing Unit, shown in FIGS. 8-14.

FIG. 1 is a front perspective view of the remote display and control unit for the wireless digital kitchen thermometer system.

FIG. 2 is a front elevation view of the remote display and control unit;

FIG. 3 is a rear elevation view of the remote display and control unit;

FIG. 4 is right side elevation view of the remote display and control unit;

FIG. 5 is a left side elevation view of the remote display and control unit;

FIG. 6 is a top plan view of the remote display and control unit;

FIG. 7 is a bottom plan view of the remote display and control unit.

FIG. 8 is a front perspective view of the remote sensing unit for the wireless digital kitchen thermometer system.

FIG. 9 is a front elevation view of the remote sensing unit;

FIG. 10 is a rear elevation view of the remote sensing unit;

FIG. 11 is right side elevation view of the remote sensing unit;

FIG. 12 is a left side elevation view of the remote sensing unit;

FIG. 13 is a top plan view of the remote sensing unit; and,

FIG. 14 is a bottom plan view of the remote sensing unit. The broken lines depict portions of the wireless digital kitchen thermometer system that form no part of the claimed design.
